UNITED STATES PATENT OFFICE.

JOSEPHINE D. LEWIS, OF SPRING LAKE BEACH, NEW JERSEY.

HAIR-BAND.

1,207,574.

Specification of Letters Patent.

Patented Dec. 5, 1916.

Application filed September 19, 1914. Serial No. 362,539.

To all whom it may concern:

Be it known that I, JOSEPHINE D. LEWIS, a citizen of the United States, residing at Spring Lake Beach, in the county of Monmouth and State of New Jersey, have invented certain new and useful Improvements in Hair-Bands; and I do hereby declare the following to be a full, clear, and exact description of the invention, such as 5 will enable others skilled in the art to which it appertains to make and use the same.

My invention relates to improvements in devices for holding the hair in place during violent exercise or when sleeping and has 15 for its primary object to provide a band which will not only hold the hair in the desired position but will permit free circulation of air about the hair or that portion of the head which the band engages.

Another object is to generally improve 20 devices of the above mentioned character, so as to render them more practical, reliable and efficient in operation and inexpensive to manufacture.

The above and additional objects are accomplished by such means as are illustrated 25 in the accompanying drawings, described in the following specification and then more particularly pointed out in the claims.

With reference to the drawings, wherein 30 I have illustrated the preferred embodiment of my invention as it is reduced to practice, and throughout the several views of which similar reference numerals designate corresponding parts, Figure 1 is a plan view of my improved band, Fig. 2 is a side elevation of my band showing it in use, Fig. 3 is a vertical sectional view taken on line 3—3 of Fig. 1, and Fig. 4 is a detail sectional view taken on line 4—4 of Fig. 2.

Referring to the drawings by characters of reference, the numeral 1 designates the body portion of my improved band which comprises a plurality of substantially elliptical strips of flexible reticulated material 45 preferably cloth netting. The body portion 1 has a relatively stiffer flexible marginal strip 2 stitched thereto and which serves to hold the layers of reticulated material or strips in operative relation to one

another, the meshes in the layers of cloth netting registering so as to permit of air passing freely through the layers of netting to the head. The body portion 1 is larger at the center or at a point centrally of its 55 ends and gradually tapers toward its ends from the center in both directions. Secured at each end of the body portion to the band 2 thereof is a flexible securing tape 3 which is provided with snap fastening elements 4. 60 The strips or tape at each end coöperate with each other to secure the device on the head of the wearer.

In use, when it is desired to retain or hold the hair in position so that it is prevented 65 dropping before the eyes or becoming deranged otherwise, the band is placed about the upper forehead and secured at the rear of the head by placing the fasteners 4 into coöperative position as shown in Fig. 4. 70 The foraminous body permits free circulation of air about the head and at the same time serves to securely hold the hair in position. The marginal band 2 in being relatively stiff serves to give body to the device. 75

In practice, I have found that the form of my invention, illustrated in the drawings and referred to in the above description, as the preferred embodiment, is the most efficient and practical; yet realizing that the 80 conditions concurrent with the adoption of my device will necessarily vary, I desire to emphasize the fact that various minor changes in details of construction, proportion and arrangement of parts may be re- 85 sorted to, when required, without sacrificing any of the advantages of my invention, as set forth.

What is claimed is:—

1. In a device for holding the hair off of the forehead comprising a body having a wide central portion and narrow ends, said body portion consists of layers of cloth netting, flexible means for holding the layers in position, and means for holding said body portion on the hair for the purpose specified.

2. In a device for holding the hair off of the forehead comprising a plurality of substantially elliptical strips of cloth net-

100

ting, a flexible binding tape secured to the marginal edges of said strips adapted to secure the same in place, said body portion adapted to encircle the front hair of the user, and means secured to the ends of said strips to engage the back of the head thereby holding the device in place.

In testimony whereof I affix my signature in presence of two witnesses.

JOSEPHINE D. LEWIS.
